Attorney

UNITED STATES PATENT OFFICE.

SAMUEL T. SCHOFIELD, OF WASHINGTON, DISTRICT OF COLUMBIA.

BANK PASS BOOK.

Application filed March 29, 1924. Serial No. 702,904.

To all whom it may concern:

Be it known that I, SAMUEL T. SCHOFIELD, a citizen of the United States, residing at Washington, in the District of Columbia, 5 have invented new and useful Improvements in Bank Pass Books, of which the following is a specification.

The invention relates to a bank book for savings systems.

10 The object of the present invention is to provide a simple, practical and efficient bank book designed for use in connection with savings systems and equipped with means for enabling it to be operated by a coin 15 operating a book controlled machine for printing in the book the amount deposited and for indicating the place of deposit by a teller designation.

20 A further object of the invention is to provide a bank book of this character adapted principally for use in connection with machines designed to be controlled by banks and similar institutions and to be installed at various places for enabling depositors 25 to deposit coins of various amounts and to receive credits in bank books without necessitating the depositors going to a bank.

Another object of the invention is to provide a bank book of this character which 30 will enable relatively small deposits of coins of different dimensions to be quickly and accurately made and receipted for, thereby reducing the banking expense of handling such money and of greatly facilitating the 35 saving of money by depositors who might otherwise find it inconvenient to deposit such small amounts.

With these and other objects in view, the 40 invention consists in the construction and novel combination and arrangement of parts hereinafter fully described, illustrated in the accompanying drawings and pointed out in the claims hereto appended, it being understood that various changes in the form, 45 proportion and minor details of construction, within the scope of the claims, may be resorted to without departing from the spirit or sacrificing any of the advantages of the invention.

50 In the drawings,

The figure of the drawing is an elevation of a bank book constructed in accordance with this invention.

55 In the drawing in which is illustrated the preferred embodiment of the invention, 1 designates a bank book provided with leaves

2, truncated at the top at 3, to expose the top portion 4 of the book which may be either leaves of the book or the inner faces of the covers of the book, and the said top portion 4 is designed to contain the name of the bank or other financial institution associated with the words "In account with" opposite which is a space 5 for the name of the depositor, but the name of the depositor may be placed at any other convenient position as will be readily understood. The name of the bank and the name of the depositors preferably occupies the left hand side of the top portion 4 and the right hand side bears a serial number 6 and a block 7 of numerals consisting of a series of rows of numerals from 1 to 9 and also include a naught, as clearly shown in the drawings and the book is punched or 75 perforated, the perforations 8 being through numerals of the said rows corresponding to the serial number of the book, and designed primarily for use in connection with mechanism of the said machine for permitting 80 the passage of pins thereof corresponding with the numerals punched, for printing the serial number of the book on a strip or tape within the machine, and also the serial number of the deposit in the bank 85 book, so that the bank or other financial institution will be able from the strip or tape and the contents of the machine to make proper entries in the books of the institution. 90

The truncated leaves 2, are ruled to provide date columns 9, a teller column 10, a serial number column 11, a deposit column 12, and also withdrawal and balance columns 13 and 14. The date column is preferably 95 provided with spaces for the day, month and year as shown. The teller column is designed to receive teller designations for indicating where the deposit was made and will preferably consist of a machine number, 100 but any other form of designation may of course, be employed. The serial number column 11, receives the serial number of the deposit in the book and is provided for insuring a duplicate record on the record 105 strip of the machine so that the records strip of the machine will contain all the necessary elements for making proper entry into the books of the institution. The amount of the deposits in the deposit column 110 12, is designed to be controlled by coins deposited in the machine with which the

book is associated. The withdrawals and balance columns are for use in balancing the book.

- The ruled horizontal lines of the pages or leaves of the bank book will be numbered consecutively from the top to the bottom so that the bank book may be arranged in proper position with relation to the record receiving means such as a strip or sheet of a machine, but the record receiving means will be absolutely accurate whether the depositor arranges the book in proper position or not. This will render the system fool proof and as an accurate record will be maintained of each deposit transaction, there will be no liability of a depositor losing anything by failing to arrange the bank book in proper position for the record of the deposit.
- Instead of employing the perforations for pins, contacts such as metallic eyelets or the like may be used for operating electrical mechanism.

The machine with which the book will be associated will form the subject matter of a separate application and while it is preferable to use the book in connection with a machine, the record may be made on a record strip for banking purposes, or on any other form of record sheet as will be readily understood.

What is claimed is:

1. A bank pass book having at least one of its cover sections provided with means adapted to co-act with suitable type elements whereby type may be selected for printing indicia for identifying the particular book.

2. A bank pass book having at least one of its cover sections provided with perforations adapted to co-act with suitable type elements, whereby type may be selected for printing indicia for identifying a particular book.

3. A bank pass book having at least one of its cover sections provided with perforations adapted to co-act with suitable type elements, whereby type may be selected for printing indicia for identifying the particular book, said book, being provided with leaves some of whose upper edges are below said perforations to prevent interference with the selective action of said perforations.

4. A bank pass book having at least one of its covers provided with perforations for the purpose mentioned, a plurality of leaves between the covers with their upper edges terminating below said perforations, and a series of symbols vertically arranged at the front edge of each leaf and adapted to indicate the position of printing in a horizontal direction upon said leaves.

5. A bank pass book having at least one of its cover sections provided with means adapted to co-act with suitable type elements, whereby type may be selected for printing indicia for identifying the particular book, said book being provided with a series of leaves therein having a series of symbols vertically arranged at the front edge of each leaf, and adapted to indicate the position of printing in a horizontal direction upon said leaves.

In testimony whereof I have hereunto set my hand.

SAMUEL T. SCHOFIELD.
